UNITED STATES PATENT OFFICE

2,424,460

INTERCEPTING ROTOR CONSTRUCTION

Henry C. Hettelsater, Whitefish Bay, Wis., assignor to Harnischfeger Corporation, Milwaukee, Wis., a corporation of Wisconsin

Original application December 13, 1943, Serial No. 514,177. Divided and this application December 11, 1944, Serial No. 567,697

2 Claims. (Cl. 37—189)

1

The invention relates to a travelling material treating apparatus for conditioning the material used for making roads or other pavements at the place of use.

This application is a division of my copending application Serial No. 514,177, filed December 13, 1943, and relates more particularly to the target or intercepting rotor of said application.

According to the aforesaid application, in the making of road or other pavements, the material operated upon by the soil treating unit is subjected to action of a rotary cutter and a target rotor to thoroughly mix and blend the material which is then transferred to a blading mill and deposited upon the road bed. During the transfer of mixed road materials they are sprayed with a suitable binder ingredient with which they are thoroughly mixed by the blading mill before being deposited on the road bed. In this apparatus the target rotor has the function of intercepting the material thrown back by the rotary cutter and returning it to the cutter for further pulverization and finally transferring the pulverized and blended material to the blading mill. It also has the further function of acting to shave or plane down any ridges of material in the subgrade left by the action of the rotary cutter, and the object of this invention is to provide a target rotor which will perform the above named functions when used in a soil treating unit of the type described.

The invention further consists in the several features hereinafter described and included in the claims at the conclusion hereof.

In the drawings:

Fig. 1 is a vertical sectional view through a material treating unit, equipped with the target rotor embodying the invention;

Fig. 2 is a plan view of the material treating unit, parts being removed, parts being broken away, and parts being shown in section.

Referring to the drawings, the material treating unit comprises a housing 2 formed of plates 84, 85, 86, and 87 and having removable top doors 88, a transverse frame member 89 to which a suspension link 71 is secured and carrying pivot pins 77 for connecting with suspension levers 36 secured to a transverse frame member 37 carrying a brace 41.

The housing 2 has four spaced shafts 90, 103, 108, and 109 journaled therein, said shafts respectively forming parts of a rotary cutter 101, a target rotor 102, and two blading mill rotors 110.

The rotary cutter has cutting tine sockets 93

2

secured thereto in which the cutting tines 96 are suitably mounted.

Spaced from and parallelly disposed to the rear of cutting rotor 101 is a target or material intercepting rotor 102 mounted on a shaft 103 having a tubular center portion with reduced end extensions carried in bearings held in the side plates 84 and 85. One of the extensions of shaft 103 passes through a bearing 104 held in the side plate 84. The tubular portion of shaft 103 is provided throughout its length with four equally spaced radially extending longitudinal fins 106 welded in place.

Attached to the fins 106 by bolting are a plurality of closely spaced resilient steel tongues 107 of uniform length, the tips of which are bent slightly as shown and cut at a slight angle so as to sweep a substantially cylindrical surface in spite of the bend of the tip. The tips of the tongues 107 are bent so as to cause material engaged by the same to move laterally to some extent. As appears more clearly in Fig. 2, some of the tongues 107 are bent to cause lateral movement of material in one direction and some in the other direction. The arrangement is such that one pair of diametrically opposed sets of tongues tends to divide material at the center of rotor 102 and move it toward the ends thereof, while the intervening pair of diametrically disposed sets of tongues tends to gather material from the ends of rotor 102 and move it toward the center. This general arrangement is subject to the exception that in the case of the sets of tongues bent to cause outward movement of material, the outer tongues designated 107A are oppositely bent to minimize loss of material beyond the ends of the rotor 102. Since the object sought is an alternate transverse mingling action of the material, other arrangements of the bent tongues 107 may be resorted to with equal effectiveness, and some modification in this regard may be found advantageous in handling different types of material.

The rotor 102 is arranged to be turned in the direction indicated by the arrow in Fig. 1 by driving means to be described more fully hereinafter. The rate of rotation of target rotor 102 is preferably such that material deposited before it and impinging upon it by reason of the action of cutting rotor 101, is moderately tossed back into the more rapidly turning cutting rotor 101 from which it is again returned forcibly into the target rotor 102. In the course of the back and forth movement of the material thus created, it is raised to successively higher levels in the target

rotor 102 until it is finally caught by the target rotor 102 and tossed rearwardly. In this way the material is subjected to repeated impact and thus pulverized to a very substantial degree. Furthermore, in cases where dry material, such as sand or Portland cement, is spread upon the surface being worked upon in advance of the apparatus while working, a very thorough mixing and intermingling of the added dry particles with the pulverized soil is accomplished. In aid of this intermingling and mixing action, the slight lateral movement caused by the bent tips of the tongues 107 brings about a lateral blending also, which tends to obliterate any lack of uniformity transversely of the work strip caused by streaked spreading of the dry material.

While the target rotor 102 is in effect a complete paddle wheel because of the close spacing of the tongue 107, each tongue is independent and resilient so that it may yield if an obstruction such as a deeply buried boulder not cut away by the resilient cutting tines of the cutting rotor 101 is encountered. Because the tongues 107 are spaced from one another slightly, and are bent at their tips and may yield and thus incompletely sweep the excavated subgrade, successive sets of tongues making up the rotor 102 are staggered slightly as may be observed in Fig. 2 to ensure engagement of all material excavated by the target rotor 102.

It is also to be noted that the blades of the target rotor have a shaving or planing action on that portion of the road bed beneath it, so that if the cutters of the rotary cutter should leave ridges of material in this road bed, such ridges will be shaved off by the blades of the target rotor.

The rotors 110 of the blading mill are provided with welded in place blade sockets 111 in which the shanks of replaceable blades 112 are mounted.

For driving the rotors a double sprocket 128 is mounted on the shaft 90 and connects by a suitable chain drive 127 with a suitable source of power. A double sprocket 129 on shaft 90 connects by chain 134 with a double sprocket 135 on shaft 135' above the shaft 103 and connected thereto by reduction gearing 132 to drive the target rotor at a lower rate of speed than the cutting rotor 101.

The shaft 135' has the double sprocket 136 mounted thereon connected by a chain 139 with a double sprocket 138 on the shaft 108 of the front blading rotor 110 and connected by gears 140, 142, 143, and 144 in a gear housing 137 with the shaft 109 of the rear blading rotor 110 whereby said rotors 109 and 110 are synchronously driven in opposite directions and at a slower rate of speed than the rotor 101.

A binder ingredient may be sprayed into the material being treated through distributor pipes 169 and 178 which are connected by a coupling 292 and which may be supplied with one or more types of binder ingredient through supply pipes 167 (one of which is shown) provided with an hydraulically operated cut off valve 168.

The general mode of operation of the above described treating unit including the target rotor is, as follows:

The rotary cutter either digs or separates the road forming material from its base and throws it into the blades of the target rotor which, as previously noted, return parts of this material to the cutting rotors, and through a successive advance and return the material is finally trans-

ferred from the upper portion of the target rotor to the blading mill. During its passage to the blading mill it is sprayed with a binder ingredient which may be a petroleum binder in the case of asphalt type pavements, or water in the case of a cement type pavement, and this binder ingredient is thoroughly intermixed with the material in the blading mill.

Material tossed rearwardly by the target rotor 102 when operating at preferred speed is delivered into the forward blading mill rotor 110 at a level centering about a plane slightly above the rotor shaft 108 from which level it is carried downwardly in front of the forward rotor shaft 108 and thence to the rear and upwardly between the two blading mill rotors where it undergoes a shearing, squeezing, and tumbling action to accomplish a thorough coating of the particles of the material with the added bonding agent. Much of this material is then thrown forwardly again over the forward blading mill rotor for return with fresh material and for a repetition of the treatment which occurs between the two blading mill rotors. The remainder of the material not carried forwardly for recycling is carried over the top of the rear blading mill rotor and deposited on the subgrade in condition for rolling to complete the pavement.

I desire it to be understood that this invention is not to be limited to any particular form or arrangement of parts except in so far as such limitations are included in the claims.

What I claim as my invention is:

1. In a target rotor for an apparatus of the class described, the combination of a shaft having a hub portion and a plurality of angularly spaced radial vanes having their shanks mounted on said hub portion and extending throughout the length thereof, said vanes comprising a series of closely spaced separate yieldable tongues of substantially uniform width from their shanks to their outer free ends and having tips angularly deflected lengthwise of the width thereof.

2. In a target rotor for an apparatus of the class described, the combination of a shaft and a plurality of angularly spaced radially disposed rows of wide faced blades mounted thereon, the blades of each row arranged in juxtaposition to form a substantially continuous blade surface but being individually yieldable and having angularly deflected tips, the deflection of the tips of the blades for some of the rows adapted to advance material from the center of the rotor toward its ends and those for other of the rows to advance material from ends of the rotor toward its center.

HENRY C. HETTELSATER.
